US00D532362S

(12) **United States Design Patent** (10) Patent No.: **US D532,362 S**
Noguchi et al. (45) Date of Patent: **** Nov. 21, 2006**

(54) **TREAD PORTION OF AN AUTOMOBILE TIRE**

* cited by examiner

(75) Inventors: **Yoji Noguchi**, Chuo-ku (JP); **Akira Yagi**, Chuo-ku (JP)

Primary Examiner—Robert M. Spear

(74) Attorney, Agent, or Firm—Sughrue Mion, PLLC

(73) Assignee: **Bridgestone Corporation**, Tokyo (JP)

(57) **CLAIM**

(**) Term: **14 Years**

The ornamental design for a tread portion of an automobile tire, as shown and described.

(21) Appl. No.: **29/226,246**

DESCRIPTION

(22) Filed: **Mar. 28, 2005**

FIG. 1 is a perspective view of an automobile tire, it being understood that the tread pattern repeats uniformly throughout the circumference of the tire.

(30) **Foreign Application Priority Data**

Sep. 30, 2004 (JP) 2004-029680

FIG. 2 is a front elevation view thereof, a top plan view and a bottom plan view are identical with the front elevation view.

(51) **LOC (8) Cl.** **12-15**

FIG. 3 is a rear elevation view thereof.

(52) **U.S. Cl.** **D12/563; D12/544**

FIG. 4 is a right side elevation view thereof.

(58) **Field of Classification Search** D12/544,

FIG. 5 is a left side elevation view thereof.

D12/549, 550, 551, 553, 554, 555, 556, 557,
D12/563; 152/209.1, 209.12, 209.28

FIG. 6 is an enlarged fragmentary front view thereof; and,
FIG. 7 is a cross-sectional view thereof taken along line
7—7 in FIG. 6.

See application file for complete search history.

The portion of the article shown in broken lines is for
illustrative purpose only and forms no part of the claimed
design.

(56) **References Cited**

In the drawings, the dark stippled surface shading represents
the recessed portion of the tread grooves, having the depth
shown in FIG. 7.
